United States Patent Office

Des. 185,539
Patented June 23, 1959

185,539

TELEVISION STAND OR THE LIKE

Maurice Duchin, New York, N.Y.; Viva Duchin, executrix of said Maurice Duchin, deceased, assignor to Maurice Duchin Creations, Inc., New York, N.Y., a corporation of New York

Application July 24, 1957, Serial No. 47,060

Term of patent 14 years

(Cl. D33—14)

FIG. 1.

FIG. 4.

Fig. 2

I claim:

The ornamental design for a television stand, or the like, as shown.
